UNITED STATES PATENT OFFICE.

WILLIAM E. BURNETT, OF ILION, NEW YORK, ASSIGNOR, BY MESNE ASSIGNMENTS, TO REMINGTON TYPEWRITER COMPANY, OF ILION, NEW YORK, A CORPORATION OF NEW YORK.

TYPE-WRITING MACHINE.

1,059,926.

Specification of Letters Patent.

Patented Apr. 22, 1913.

Application filed March 6, 1911. Serial No. 612,502.

To all whom it may concern:

Be it known that I, WILLIAM E. BURNETT, citizen of the United States, and resident of Ilion, in the county of Herkimer and State 5 of New York, have invented certain new and useful Improvements in Type-Writing Machines, of which the following is a specification.

My invention relates to improvements in 10 typewriting machines and more particularly to means for effecting a quicker and more accurate centralization of lines for headings and the like. Usually this work is done by mentally deciding upon a center point on 15 the carriage scale as a center, say, the number "35" when the entire travel of the carriage is seventy spaces, then counting the number of letters and spaces in the line to be centered, halving the same, deducting the 20 result from "35" and so obtaining on the scale the point where the line comprising the heading is to be started and so on with each subsequent line of the heading.

The main object of my invention, generally 25 stated, is to simplify this procedure, obviate the necessity of any appreciable mental calculation, provide a centering indicator and thus minimize the risk of deviation from the center; relieving the mind of the operator 30 of mental strain and facilitate the production of work of the character specified, whether the heading is to be centered with reference to the work sheet or with reference to a previously written line or lines 35 on the work sheet and irrespective of the point where said line or lines terminate.

A further object of my invention is to provide simple and efficient means for readily centering a work sheet with reference 40 to the platen.

To the above and other ends which will hereinafter appear my invention consists in the features of construction, arrangements of parts and combinations of devices to be 45 set forth in the following specification and particularly pointed out in the appended claims.

In the accompanying drawings, wherein 50 like reference characters indicate corresponding parts in the various views, Figure 1

is a fragmentary front elevation of the upper portion of one form of typewriting machine embodying my invention. Fig. 2 is a fragmentary detail front view with parts in section of the auxiliary centering scale at the 55 front of the machine. Fig. 3 is an enlarged detail fragmentary perspective view showing the right-hand end of the centering scale illustrated in Fig. 2. Fig. 4 is a detail front view of the work sheet centering scale together with the side edge gage carried thereby. Fig. 5 is an end view of the parts shown in Fig. 4. Fig. 6 is a vertical, front to rear, sectional view of the upper portion of a machine with the devices of my invention 65 embodied therein. Fig. 7 is a representation of a work sheet with one form of heading inscribed with the aid of my invention. Fig. 8 is a view of a work sheet showing an offset heading thereon inscribed with the 70 devices of my invention.

I have shown my invention embodied in the present instance in a No. 10 Remington machine, although it should be understood that the invention may be embodied in various 75 styles of typewriting machines.

The corner posts 1 of the machine support a top plate 2 provided with guide rails 3 oppositely grooved to receive anti-friction balls or rollers 4 which are likewise received 80 in forward and rear guide bars 5 and 6, respectively, of the carriage; such bars 5 and 6 constituting the front and rear cross bars respectively of the carriage which are united by end bars 7. A rotative platen 8 is mounted 85 in the usual manner in the carriage; a platen shaft 9 extending through bearing openings in the platen frame 10, mounted for vertical case shifting movement on parallel links 11 and supported by a shift rail 12. Rearwardly extending arms 13 of the platen frame support a cross bar 14 on which a paper table 15 is supported in the usual manner. Some of the parts of the machine are omitted. It should be understood, however, that the paper is introduced into the machine in the usual manner from the rear of the platen into the bight or throat between the main paper feed rollers 16 (indicated in dotted lines in Fig. 6) and the 95 100

platen. A cross bar 17 extends between the arms 13 of the platen frame and constitutes a support for perforated bracket arms 18, each of which is held fixed to the rod 17 by a set screw 19 received in a tapped opening in the bracket arm and bearing at its free end against the rod 17. The upper ends of the bracket arms support a work sheet centering scale plate 20 which is fixed to the arms and extends throughout, or substantially throughout, the length of the platen. This centering scale plate is supported independently just below the lower end of the paper table and between the paper table and the platen in such position that the work sheet, as it is introduced into the machine, may coöperate with the indices on the work sheet centering scale. From an inspection of Fig. 4 it will be seen that the scale plate 20 is provided with the usual index marks 21 arranged a letter space distance apart and corresponding in this respect to the usual carriage scale. Numerical indices 22 are likewise provided upon the scale plate 20. These numerical indices, however, begin at the outer ends of the scale plate and progress to the center thereof. It will be observed that in the present instance the numerical indices extend from "0" at each end of the scale bar to the center thereof which is indicated at "45". This point "45" indicates the center of the platen and the scale marks extend on each side thereof throughout the length of the platen in order that the side edges of the work sheet may coöperate with the indices near each end of the scale plate, depending on the width of the work sheet. I preferably provide a sheet metal supporting member 23 which partly surrounds the scale plate 20 and has projecting forwardly therefrom an extension or finger 24 which extends at right angles to the axis of the platen and constitutes a side edge gage for the paper. I have shown but one of these side edge gages but it will be understood that two of them may be employed, one near each end of the scale plate 20. The support 23 for the side edge gage loosely surrounds the scale plate 20 so as to enable the support, with the side edge gage 24 formed thereon, to be adjusted longitudinally of the scale plate; there being sufficient friction between the support or carrier 23 and the scale plate to maintain the support and side edge gage in the position to which they may be adjusted. It will be understood that the work sheet centering scale enables the operator to properly center the plate with reference to the platen as the work sheet is introduced into the machine. If, for instance, the width of the paper corresponds to sixty spaces on the scale plate 20, each side edge of the sheet should register with the numerical index "15" at the associated end of the scale plate 20 and the sheet will be prop-

erly positioned centrally of the platen and the gage 24 may be set accordingly. If subsequent sheets are of the same width the side edge gage will enable all of the sheets to be readily inserted and properly centered without consulting the scale 20. 70

Upon referring to Fig. 6 it will be observed that a fixed pointer 25 is secured by a screw 26 to a bracket plate 27 which in turn is fixed to the forward fixed guide rod 3 by screws 27^a (Fig. 1); the pointer being thus maintained fixed at the center of the machine and extending upwardly and then forwardly to coöperate with a carriage scale 28 secured to the front cross bar 5 of the carriage. The carriage scale 28 is of the usual character with letter space index marks 29 and numerical indices 30 thereon. In the present instance these numerical indices progress from left to right beginning at "0" and terminating at "70", it being assumed that in the present instance the carriage has a complete travel of seventy-six letter spaces. 80 85

An auxiliary, multiplex, centering-scale bearing-member 31 is provided for centering headings and the like with reference either to the work sheet or to a previously printed line irrespective of the point where the line terminates. This scale bearing plate is provided with or constitutes a multiplex scale; one scale 32 being provided on one side thereof and another scale 33 being provided on the other side of the plate. From an inspection of Fig. 1 it will be seen that the index marks 34 on the scale 32 correspond in their spacing to the carriage scale; and that the numerical indices likewise correspond to the carriage scale and extend progressively in the same direction as the numerical indices on the carriage scale, *i. e.*, from left to right 100 commencing at "0" and extending to "70". The numerical indices on the auxiliary scale 32 however are five spaces apart instead of ten as is the case on carriage scale 28. Upon referring to Fig. 2 it will be seen that 110 the scale 33 on the opposite side of the multiplex scale-bearing plate has its indicating marks 35 arranged like the scale 32 and like the carriage scale 28. The numerical indices "0" to "70", however, progress in the opposite direction from the numerical indices on the scale 32 and in an opposite direction from those on the carriage scale and are spaced apart like the numerical indices on the scale 32. Preferably the numerical indices on the scale 32 are in black whereas those on the scale 33 are preferably in a distinctive color, as red, for instance. It will be seen, moreover, that the scales 32 and 33 correspond to about one-half of the length of the carriage scale and the space between each adjacent set of index marks is therefore twice the value as will hereinafter more clearly appear. In short, a letter space movement of the carriage corresponding to 120 130

a movement of the carriage scale from one letter-space index mark to the next will be represented as twice the value or two letter spaces on either of the scales 32 and 33. 5 The scale bearing plate 31 is mounted on the frame of the machine so that it may be turned to expose either of the scales 32 or 33 to the operator, or to maintain the scale bearing plate presented edgewise to the operator, as indicated in dotted lines in Fig. 6, so as to throw the centering scale out of use in order to avoid confusion. Thus, it will be seen that the left-hand end of the scale bearing plate 31 is provided with a 10 knurled head 36 by which the scale bearing plate may be turned. One end of the plate is apertured at 37 to receive a supporting pivot pin 38 riveted to a supporting bracket 39, secured to the forward fixed guide rod 3 20 of the machine. An expansion spring 40 is received in the aperture in the plate 31 and tends to force the plate longitudinally to the right. The right-hand end of the plate 31 has shoulders 41 formed thereon to limit the 25 movement of the plate to the right, said shoulders bearing against a bracket arm 42 carried by the bracket 27. A rectangular engaging portion 43 is formed near the right-hand end of the plate 31 and this rec- 30 tangular bearing portion is adapted to be received in a corresponding bearing opening in the bracket arm 42, so as to hold the scale plate against rotative movement in any one of three different positions. In one of these 35 positions the scale 32 may be exposed to the operator, as shown in Fig. 1; in another position the scale 33, at the opposite side of the scale plate, may be exposed to the operator as indicated in Fig. 2; or the scale plate 40 may be supported in a third position, presenting it edgewise to the operator, as indicated in dotted lines in Fig. 6, so that neither of the scales 32 or 33 is presented to the view 45 of the operator. Extending to the right of the rectangular bearing portion 43 on the scale plate is a cylindrical bearing or pivot portion 44 which supports the scale plate in the bearing opening in the bracket arm 42 when the scale plate is shifted longitudinally to the left against the pressure of the 50 spring 40, to disengage the rectangular bearing portion from the bearing opening in the bracket arm 42. When such longitudinal movement of the scale plate has been effected 55 it is free to be rotated to bring either of the scales 32 or 33 to the view of the operator or to present it edgewise to the operator as hereinbefore described.

A left-hand end plate 45 on the front 60 cross bar 5 of the carriage is extended forwardly at 46 to form a pointer or indicator which coöperates with either of the scales 32 or 33 on the multiple scale bearing plate 31. This pointer is indicated in Fig. 1 and 65 is shown in dotted lines in Fig. 6. The

pointer 46 being carried by the carriage at the front of the machine and the auxiliary multiplex-scale bearing-plate 31 being carried by the frame of the machine at the front thereof, it follows that letter space movements of the carriage cause a relative movement between the pointer and either of the scales 32 or 33 which is exposed to the operator, and that the relation of the pointer to the exposed auxiliary scale may be at all 70 times readily observed by the operator. 75

The devices are used somewhat differently, depending on the nature of the work to be produced or the character of the heading to be inscribed. Assuming that a heading such as that indicated at *a* in Fig. 7 is to be inscribed, so that it shall be properly centered with reference to the sheet *b*, the work sheet is first inserted and centered with reference to the platen by the work sheet centering-scale 20 in the manner hereinbefore indicated. The scale bearing member 31 is then adjusted so as to present the black scale 32 to the operator, as indicated in Fig. 1. The number of characters and spaces in the first line of the heading to be inscribed is then counted. Thus it will be found that the line containing the words "John Doe's" in the heading *a* contains ten characters and spaces. The carriage is then moved until the pointer 46 is at "10" on the auxiliary scale. The heading may then be printed and it will be found to be properly centered on the sheet; the heading beginning at the index mark indicated at thirty-three in the 80 carriage scale and ending at the index mark indicating the point forty-three. Ten spaces occupied by the heading added to thirty-three spaces to the left of the heading and thirty-three spaces to the right of the heading makes a total of seventy-six spaces, corresponding to the entire travel of the carriage. 85 90 95 100 105

In the second line of the heading *a* which includes the words "School of instruction" 110 there are twenty-two characters and spaces. The carriage is moved until the pointer 46 registers with the index mark indicating the position twenty-two on the auxiliary centering-scale 32. The line is then written and 115 will be commenced at the index on the carriage scale corresponding to the point twenty-seven. It will be found that there will be twenty-seven spaces on either side of the written line and this added to twenty-two 120 spaces occupied by the heading "School of instruction" makes a total of seventy-six, corresponding to the entire length of travel of the carriage.

It is sometimes desirable to provide an 125 off-set heading, the different lines of which may be centered with reference one to another without taking into consideration the center of the sheet. In other words, it is often desirable to place a heading, or to add 130

a short line, either above or below a previously written line and to properly center the heading with reference to the previously written line, irrespective of the point where the latter terminates. An example of this is illustrated in Fig. 8. In writing headings of this character, the work sheet centering scale 20 may be ignored. In writing an off-set heading such as that shown in Fig. 8 10 the work sheet is inserted in the machine with the left-hand margin thereof at the extreme left-hand of the platen. The auxiliary multiplex-scale bearing-member 31 is then rotatively adjusted to bring the red 15 scale 33 to the view of the operator, as shown in Fig. 2. This scale is of less length than the carriage scale and its graduations have double the value of those of the carriage scale and said graduations diminish in 20 numerical value as the carriage is moved toward the right, said scale indicating zero when the carriage is in its extreme right-hand position and indicating its highest number when the carriage is at the middle of 25 its run. The previously written line, which may be assumed to be the line *c* in Fig. 8, begins at "0" on the carriage scale and terminates at "40" in the example shown. If the operator desires to place the words 30 "Experienced instructors" beneath the line *c* and to properly center the added words with reference to the previously written line, it is merely necessary to count the number of characters and spaces for the added heading 35 "Experienced instructors". This will be found to occupy twenty-four spaces. Deduct twenty-four from forty, which is the number of spaces required for the previously written line, and this will leave sixteen 40 spaces. The carriage may then be moved until the indicator 46 registers with the index mark which indicates sixteen on the scale 33. The operator may then proceed 45 to write the line *d* "Experienced instructors" and it will be properly centered with reference to the previously written line, although the latter is off-set with reference to the sheet *b*, as indicated in Fig. 8. In short, it is merely necessary, in order to arrive at 50 a proper centering of one line with reference to another, to deduct the number of spaces occupied by the added line from the number of spaces contained in the previously written line and then set the pointer 46 on 55 an index mark on the scale 32 which corresponds to the remainder after the deduction referred to above has been made. This will afford a positioning of the carriage to properly center the added line.

60 From the foregoing description it will be understood that I have provided simple and efficient devices for centering a heading with reference to a sheet or for centering a heading or added line with reference to a pre-

viously written line irrespective of the point 65 at which the previously written line terminates.

Various changes may be made without departing from the spirit and scope of my invention.

What I claim as new and desire to secure by Letters Patent, is:—

1. In a typewriting machine, the combination of a carriage, means for aiding in positioning the carriage to center the work to be produced with reference to the sheet, and means for aiding in positioning the carriage to center the work to be produced with reference to an off-set line written on the sheet and irrespective of the point where 80 said line terminates.

2. In a typewriting machine, the combination of a carriage, a platen, means for centering a work sheet on said platen, means for centering a heading on said work sheet, 85 and means for centering a line relatively to another line off-set from the center of the sheet.

3. In a typewriting machine, the combination of a carriage, a rotative platen carried thereby, an auxiliary multiplex centering-scale-bearing member having numerical indices on different scales progressing in opposite directions and each set of numerical indices having double the value of those of the 95 ordinary carriage scale, and means for enabling either one or another of the scales to be presented for use.

4. In a typewriting machine, the combination of a carriage, a rotative platen carried thereby, an auxiliary multiplex centering-scale bearing member having corresponding scale marks and numerical indices on different sides thereof, the numerical indices on the different scales however progressing in 100 opposite directions and each set of numerical indices having double the value of those of the ordinary carriage scale, an indicating device co-operative with said scales, means for effecting a relative movement between 105 said indicating device and the multiplex scale bearing member during the travel of the carriage, and means for bringing any scale of the scale bearing member into co-operation with said indicating device.

5. In a typewriting machine, the combination of a carriage, a rotative platen carried thereby, an auxiliary multiplex centering-scale bearing member having corresponding scale marks and numerical indices on different sides thereof, the numerical indices on the different scales however progressing in opposite directions, an indicating device co-operative with said scales, means for effecting a relative movement between 110 said indicating device and the scale bearing member during the travel of the carriage, 115 means for bringing any scale of the scale bearing member into co-operation with said indicating device.

120

125

scale bearing member into coöperation with said indicating device, and an additional centering scale coöoperative with the work sheet for centering the work sheet with reference to the platen.

6. In a typewriting machine, the combination of a carriage, a rotative platen carried thereby, an auxiliary multiplex centering-scale bearing member having corresponding scale marks and numerical indices on different sides thereof, the numerical indices on the different scales progressing in opposite directions, an indicating device coöoperative with said scales, means for effecting a relative movement between said indicating device and the scale bearing member during the travel of the carriage, means for bringing any scale of the scale bearing member into coöperation with said indicating device, and an additional centering scale coöoperative with the work sheet for centering the work sheet with reference to the platen, said last mentioned scale having corresponding numerical indices at opposite sides thereof, said indices progressing from the ends toward the center of the scale.

7. In a typewriting machine, the combination of a carriage, a rotative platen carried thereby, a paper table arranged in the rear of the platen, and a centering-scale supported between the paper table and the platen and coöoperative with a work sheet as it is introduced into the machine, said centering scale having the numerals applied thereto progressing in opposite directions in the halves of said scale.

8. In a typewriting machine, the combination of a carriage, a platen carried thereby, and a centering-scale carried by the carriage and coöoperative with the work sheet as it is introduced into the machine, said centering scale having corresponding numerical indices at opposite ends thereof, said indices progressing in opposite directions in the halves of the scale.

9. In a typewriting machine, the combination of a carriage, a rotative platen carried thereby, a paper table arranged in the rear of the platen, and a centering-scale interposed between the paper table and the platen and coöoperative with a work sheet as it is introduced into the machine, said centering scale having corresponding numerical indices at opposite ends thereof, said indices progressing in opposite directions in the halves of the scale.

10. In a typewriting machine, the combination of a carriage, a frame of the machine, an auxiliary multiplex centering-scale bearing member carried by the frame of the machine and mounted for turning movement thereon, duplicate scale marks and numerical indices on opposite sides of said scale, the numerical indices progressing in

opposite directions, and an indicator carried by the carriage and coöoperative with the indices on one side or another of the scale bearing member according to the rotative adjustment of the latter.

11. In a typewriting machine, the combination of a carriage, a carriage scale having letter space scale marks and numerical indices, two auxiliary centering scales each substantially half the length of the carriage scale and the numerical indices on said auxiliary scales progressing in opposite directions, an indicator for coöperation with the auxiliary scales, and means for bringing either one of said auxiliary scales into coöperation with said indicator.

12. In a typewriting machine, the combination of a carriage, an auxiliary scale plate having centering-scales on opposite sides thereof, means whereby said plate may be rotatively adjusted to present either of the scales on opposite sides thereof to the operator, or the edge of the scale plate may be presented to the operator to throw the auxiliary scales out of use, and an indicator coöoperative with either of the scales on opposite sides of the scale plate.

13. In a typewriting machine, the combination of a carriage, a carriage scale, an auxiliary scale bar or plate having corresponding scales on opposite sides thereof each of double the letter space value of the carriage scale and substantially one half the length of the carriage scale, means whereby the scale plate or bar may be rotatively adjusted to present the scale on either side thereof to the operator, and an indicator coöoperative with the scale on either side of the auxiliary scale plate or bar.

14. In a typewriting machine, the combination of a carriage, a rotative platen carried thereby, a paper table arranged in the rear of the platen, a centering-scale supported between the paper table and the platen and coöoperative with a work sheet as it is introduced into the machine, and a side edge gage adjustable relatively to said scale and with which a side edge of a work sheet is adapted to coöperate.

15. In a typewriting machine, the combination of a carriage, a platen carried thereby, a centering-scale carried by the carriage and coöoperative with the work sheet as it is introduced into the machine, said centering-scale having corresponding numerical indices at opposite ends thereof, said indices progressing in opposite directions in the halves of the scale, and a side edge gage adjustable along said scale and coöoperative with a side edge of a work sheet as the sheet is introduced into the machine.

16. In a typewriting machine, the combination of a carriage, a carriage scale, a centering scale of less length than said carriage

scale and having graduations of double the value of those of said carriage scale, said graduations diminishing in numerical value as the carriage is moved toward the right.

5 17. In a typewriting machine, the combination of a rotative platen, a paper table in the rear of the platen, a side edge paper gage coöperative with the work sheet as it is introduced into the machine in the rear

10 of the platen, and means below the lower edge of the paper table for supporting the

gage for adjustment longitudinally of the platen and intermediate the ends of the paper table.

Signed at Ilion, in the county of Herkimer, and State of New York, this 2nd day of March, A. D. 1911.

WILLIAM E. BURNETT.
